UNITED STATES PATENT OFFICE.

JOHN M. WRIGHT, OF BIRMINGHAM, ALABAMA.

FROSTPROOF FLUSH DRAIN AND SUPPLY VALVE.

Application filed November 24, 1919. Serial No. 340,135.

To all whom it may concern:

Be it known that I, JOHN M. WRIGHT, a citizen of the United States of America, residing at Birmingham, in the county of Jefferson and 5 State of Alabama, have invented certain new and useful Improvements in Frostproof Flush Drain and Supply Valves, of which the following is a specification.

My invention relates to frost-proof drain 10 and supply valves for closets, hydrants, street washers and the like.

It is characteristic of my invention, in its various forms, that the valve stem shall project upwardly through the valve body and 15 carry loosely on a squared lower portion thereof an inverted valve seat which, turning with the valve stem, can be screwed into and seated tight against a seat in the lower part of the valve body. A supply valve 20 which is adapted to close with the pressure is carried by the valve stem which is guided in its vertical movements by a spider guide in the removable supply valve seat. By this arrangement the entire valve mechanism can 25 be readily unscrewed and removed from the valve body and after being repaired can be placed without disturbing the valve body, the seat and valve being removable by turning the upper end of the valve stem which 30 is conveniently accessible.

A further object of my invention is to hang the valve loosely on the lower end of the valve stem so that it will close tight whether or not the seat is true.

35 A further object of my invention as designed for the pressure tank and frost-proof closets is that the water pressure will co-act with the valve seating spring to raise the closet seat, thereby enabling a smaller and 40 lighter spring to be employed. Moreover, by arranging the spring in a chamber at the top of the compound valve body and providing a packing or stuffing box to protect the spring chamber from access of 45 water, I protect the spring from water and by packing the spring in grease its life can be indefinitely prolonged.

A further object of my invention is to adapt the valve to be removed for repairs 50 without having to do anything but detach a sleeve nut at the top of the valve body and apply a wrench to the spring chamber which turns with it the valve stem to unscrew the seat.

55 A further object is to make the drain valve out of flat washers carried by a spider ad-

justable on the valve stem, which stem can be readily lengthened or shortened by the provision between the drain and flush valves of an attachable section made or cut to the 60 desired length to properly space the said valves relatively.

It is a further object to so design the parts that the whole valve mechanism can be taken apart with an ordinary wrench, as no bolts 65 or screws are used except in hydrants.

My invention further comprises the novel details of construction and arrangements of parts, which are more particularly described and claimed in their preferred embodiments 70 only in the accompanying drawings, in which:

Fig. 1 shows in side elevation a frost-proof closet equipped with my valve mechanism.

Fig. 2 is an enlarged vertical sectional view through the valve body shown in Fig. 1.

Figs. 3 and 4 are cross sectional views taken on the lines 3—3 and 4—4 of Fig. 8.

Fig. 5 is a detail view of the coupling shown in Fig. 8.

Fig. 6 is a detail view showing the loose connection for the supply valve to its stem.

Figs. 7 and 8 are views corresponding to 85 Fig. 1 of modifications of my invention as applied to a pressure tank closet and a frost-proof hydrant, respectively.

Similar reference numerals refer to similar parts throughout the drawings.

As illustrated in Figs. 1 and 2, I show an ordinary type of frost-proof closet comprising a water supply pipe 1 connected to the lower valve body 2, which is connected by a pipe 3 to the upper valve body 4. This 95 latter valve body is connected by a pipe 3^a to the pressure tank 3^b overhead and by a flush pipe 5 to the bowl 6. The upper valve body 4 is provided with bracket arms 7 to which the hinge fittings 8 of the closet seat 9 are pivoted so as to overhang the valve body.

The valve mechanism comprises an inverted seat 10 formed preferably as an integral part of the rim 11 of the spider 12, 105 the hub 13 of which is provided with a square hole through which a square valve stem 14 passes loosely and has its lower end keyed in a sleeve 15 which has its bottom end contracted so as to hold the ball 16 on 110 a hanger rod 17 which carries the supply valve formed by a flat non-metallic washer

18 mounted between the metallic washer retainers 19 and 20, see Fig. 6, which are held in place by a nut 21 screwed on the rod. The valve 18 is thus free to adjust itself and seat 5 tightly against the seat 10 when the valve stem is drawn upwardly through the spider. A washer 22 is mounted around the upper end of the valve seat at its point of juncture with the threaded rim 11 of the spider, the 10 washer being mounted in a countersunk groove in the rim so as to be removable therewith. The valve body is provided with a seat 23 at the base of its threaded portion 24 into which the rim 11 screws and the washer 22 thus serves to insure a tight joint between 15 the seat 23 and rim 11, and the washer being removable with the rim can be readily replaced. The upper end of the stem 14 is socketed to receive a square connecting rod 20 which is keyed in the socket of the stem 14 and at its upper end is keyed into the socket of a depending central boss 26 preferably formed integral with the metallic flush-valve retainer 27. The boss 26 is 25 threaded to receive a nut 28 which holds the flat washer valve 29 in position on the under-face of the retainer 27 and this washer is adapted to engage a seat 30 in the valve body 4. The retainer 27 at its upper end is provided with a squared socket into which the 30 lower end of a square spring rod 31 is inserted and keyed, the top end of said rod being threaded and screwed into the upper inverted telescoping sleeve 32 of the spring chamber. This sleeve telescopes over a lower 35 sleeve 33 which is integral with a body portion 34 having flattened faces to form a wrench grip and is also integral with a flange 35 adapted to rest on a washer 36 on the top of the valve body 4. The lower end 40 of the sleeve 33 is closed except for a square hole through which the spring rod 31 slides, and a spring 37 surrounding the rod in the spring chamber bears at its upper end against 45 the sleeve 32 and at its lower end against a metallic washer 38 between which and the bottom of the sleeve member 33 is introduced 50 packing to form a stuffing box 39 that will prevent the leakage of water from the valve body 4 into the spring chamber, which, if desired, can be packed with grease. A screw cap 40 is adapted to screw onto the top of the valve body 4 and to draw the flange 35 with a tight fit against the washer 36 and 55 thus close the top of the valve body 4.

Where the fixture is of the frost-proof type, a small drain pipe 41 is arranged in the lower valve body 2 just above the supply valve and this connects to the sewer system 60 and serves to drain off the water remaining in the valve body after the supply valve 18 is closed. In order to prevent the leakage of water through this drain valve while the supply valve is open, I mount on the valve 65 stem 14 a valve formed by one or more non-

metallic washers 42 which are mounted on the rim of a spider 43 that can be set at any desired adjustment on the stem 14 by means of the set screw 44. A nut 45, screwed on the rim of the spider, holds the washers in 70 place and the washers form a valve adapted to close the drain pipe 41 when the supply valve is in open position.

The description as given applies equally to the pressure closet illustrated in Fig. 7, except that here the drain 41 is not required and the valve therefor is omitted. Here the valve body is short and formed as an integral casting thus omitting the pipe 3, it being unnecessary to place the supply valve 80 in the ground as in Figs. 1 and 2.

For the hydrants, the description of parts for the supply valve and its seat, the drain pipe and the drain valve are as already described, but where the compression type of 85 valve operating mechanism is employed I provide the rod 46, corresponding to 25, with a square head 47 at its upper end which is received in a coupling box 48 opposite the joint between the faucet 49 and the coupling 90 flange 50 at the top of the pipe 3. The box 48 is provided top and bottom with slots 51 through which the head on the rod 46 and a round head 53 on an operating rod 52 can be inserted into the coupling box. The rod 52 is screwed into a boss 54 on the faucet and passes through a stuffing box 55 and has on its upper end a handle 56. A set screw 57 is used to attach the box 48 to the head 47 on the valve stem 46.

In assembling the valve mechanism the screw cap 40 is removed and the entire valve mechanism, as shown in Figs. 1 to 7, is lowered into the valve body until the threaded seat rim 11 engages the threaded section 24 of the valve body, after which a wrench is applied to the grip 34 and turned to screw the seat down until the washer 22 is compressed between rim 11 and the valve body seat 23. The several valves, before being 105 thus introduced into the body, are properly spaced on the valve stem so that when the valve 29 seats the valves 32 will close the drain 41 and when the supply valve 18 seats the valve 42 will open the drain 41. The screw cap 40 is then replaced and screwed down until it clamps the flange 35 against the washer 36 to secure a tight top closure for the valve body 4. As thus arranged, the 110 valves are operated by the depression of the seat 9 and by the counteraction of the spring 37 and the water pressure on the supply valve 18. When the seat is depressed, the top valve chamber sleeve 32 is forced downwardly carrying with it the spring rod 31, 115 compressing the spring 37, seating the flush valve 29, closing the drain 41 and opening the supply valve 18. When the seat is released, the combined action of the spring 37 and pressure on valve 18 will seat the latter 120

valve and open the drain and open the flush valve. To remove the valve mechanism for inspection and repair, the screw cap 40 is taken off and all of the valve mechanism is 5 lifted upwardly out of the valve bodies, after the supply valve seat has been unscrewed from the body.

In the case of the compression hydrant shown in Fig. 8, when the faucet is disconnected from the collar 50, the former is shifted to disconnect the rod 52 from the coupling box 48, after which a wrench is applied to the box 48 or to the head 47 and the latter is turned to unscrew the valve seat 10 from the body, thus permitting the valve mechanism to be lifted out, adjusted and replaced as has been already described.

This invention is not intended to be restricted in scope to the specific embodiments 20 shown, but contemplates such modifications as come within the spirit and scope of the claims.

Having thus described my invention, what I claim as new and desire to secure by Letters Patent, is:—

1. In a valve mechanism of the character described, a valve body having a top opening and a lower inverted valve seat screwed into

the valve body and upwardly removable through said top opening, a valve stem carrying a valve for co-operating with said seat, and means on the stem to unscrew said inverted seat and remove it with its valve through the top opening of the valve body, said body having a removable top closure 30 formed with a spring chamber through which said valve stem projects, said chamber having packing in the bottom and containing oil, a spring working in said chamber and tending to move the valve stem to seat said 35 valve, and a telescoping cover for said chamber carried by the valve stem.

2. A valve mechanism in accordance with claim 1, in which said closure portion carrying the spring chamber is mounted by a 45 screw collar on the valve body and is provided with a wrench grip and a squared opening for the valve stem, said valve stem being squared throughout the portion that is movable through said top closure. 50

In testimony whereof I affix my signature.

JOHN M. WRIGHT.
